METHOD OF AND MACHINE FOR MAKING
BLANKS

Cutler D. Knowlton, Rockport, and George F. C. Burke, Fairhaven, Mass., assignors to Hoague-Sprague Corporation, Lynn, Mass., a corporation of Massachusetts

Original application March 26, 1942, Serial No. 436,362. Divided and this application December 4, 1943, Serial No. 512,856

13 Claims. (Cl. 93—58.4)

1

This application relates to the manufacture of box blanks such, for example, as that illustrated in United States Letters Patent No. 1,811,135, granted June 23, 1931, on an application filed in the name of C. D. Knowlton. The present application is a division of an application for Letters Patent of the United States, Serial No. 436,362, filed March 26, 1942, in our names.

In the manufacture of box blanks as disclosed in the aforementioned application, webs of shell, cover and lining material are continuously combined to form a web of blank material from the end of which discrete blanks are severed and fed step by step past a plurality of forming stations at each of which an operation is performed toward the completion of a box blank. The present application is concerned with that station at which slots are formed in the blank to separate the end-wings and the corner-laps and the outer edges of the end-wings are cut away to accommodate the thickness of the material where the end-wing extensions are folded over the corner-laps during the setting up of the blank to box form.

An object of the present invention relates to the provision of an improved mechanism for performing the above operations. To this end, four sets of knives are provided for forming the slots and the cutaway portions at the outer edges of the end-wings in a single operation. To accommodate blanks of various sizes, provision is made for adjusting the knives relatively to one another. As illustrated herein, the sets of knives are arranged in pairs, each pair being adjustable as a unit toward and away from the other pair, and the sets of each pair are adjustable simultaneously toward and away from each other. Provision is also made for adjusting the knives of each set toward and away from each other.

Another object of the invention relates to the provision of improved means for forming the slots between the end-wings and corner-laps in a manner to provide a finished appearance for the edges of the end-wings which are visible in the completed box, and to the method by which this is accomplished. In the attainment of this object the edges of the end-wings along the slots separating them from the corner-laps are so treated that the cover paper extends over the edges. This is effected in the illustrated embodiment of the invention by turning the marginal portions of the end-wings inwardly when the blank is severed to form the inner edges of the corner-laps, after which the inwardly projecting portions are severed in substantially the plane of

the inner face of the blank to form the edges of the end-wings with the cover paper extending thereover to the inner face of the blank. It will of course be obvious that this method of forming the slots is applicable in those cases in which the blank is not provided with cover paper. When such a blank is treated, the outer surface of the blank will extend over the edge, thus eliminating the raw edge that would be formed by the conventional slotting methods.

The above and other features of the invention, including various novel details of construction and combinations of parts, will now be more particularly described with reference to the accompanying drawings, and pointed out in the claims.

In the drawings,

Fig. 1 is an end elevation, partly in section, of one form of apparatus by which the present invention may be carried out;

20 Fig. 2 is a section on the line II—II of Fig. 1, on a larger scale than Fig. 1;

Fig. 3 is an exploded view of one of the mechanisms for forming the slot between a corner-lap and an end-wing;

25 Fig. 4 is a view, partly in section, of one of the sets of work engaging members;

Fig. 5 is a plan view of a blank as it appears after being severed from a compound web of sheet material;

30 Fig. 6 is a plan view of the blank after it has been operated upon by the present apparatus;

Fig. 7 is a perspective view on a greatly enlarged scale indicating how the cover paper hides the edge of the end-wing when the blank is operated upon by the mechanism of Figs. 3 and 4; and

Fig. 8 is a perspective view of a portion of a box illustrating the appearance of the covered edge of the end-wing in the completed box.

One form of blank upon which the machine illustrated herein is designed to operate is shown at *a* in Fig. 5 and comprises a layer of shell material *b*, a liner *c*, and a layer of cover paper *d*. The cover paper may be folded around the edges of the blank at *e* to provide a finished appearance. The blank is operated upon by the present machine to form slots *f* which separate the end-wings *g* from the corner-laps *h*. The outer edges of the corner-laps are also cut away at *j* to accommodate the thickness of the material where the end-wing extensions are folded over the corner-laps during the setting up of the blanks to box form. Side-wings *k* extend between the corner-laps *h*. After the blank is thus operated upon, it passes successively through other stations as illustrated in the parent application re-

ferred to above to complete the formation of the box blank.

The machine is built on a frame which comprises supporting bars 10 extending lengthwise of the machine and supported on the floor. Extending upwardly from the bars 10 are posts 12 to the upper ends of which are fastened rails 14 which extend lengthwise of the machine. The posts 12 are connected by a cross bar 16 and the rails 14 are interconnected by one or more cross bars (not shown) to provide a rigid frame work.

The blanks are fed through the machine with the folded edges *e* extending normal to the direction of feed by a pair of endless belts 18 which engage opposite sides of the blank and which feed the blank into engagement with a pair of stops 20 mounted on shafts 22 for movement from the positions illustrated in Fig. 1, downwardly into the path of movement of the blank. With the forward motion of the blank thus arrested the blank is operated upon as will be described, after which the stops are returned to the positions illustrated and the blank resumes its forward movement through the machine. In order to accommodate blanks of different sizes the stops 20 are carried by slides 24 which are mounted for lateral movements on a rack 26 extending crosswise of the machine. This rack is secured to the upper ends of posts 28, the lower ends of which are secured to the rails 14. Pinions 30 carried by shafts 32 supported in the slides 24 engage teeth in the upper surface of the rack bar 26 to effect lateral movement of the slides 24 and the stops 20 carried thereby upon turning the shafts 32.

Prior to operating on the blank after it has come to rest against the stops 20, the blank is properly centralized in the machine by a pair of joggers 34 having ends provided with notches for engagement with the opposite edges of the blanks. The joggers are adjustably mounted in the upper ends of arms 36, the lower ends of which are secured to slides 38 movable transversely of the machine on slideways 40 formed along the upper sides of cross bars 42 suspended by hangers 44 from the rails 14. The slides 38 are provided with rack bars 46 engageable with pinions 48 which are operated at a predetermined time to move the joggers toward each other to centralize the blank and then to retract the joggers while the blank is being operated upon. The pinions 48 are operated by a gear 50 mounted on a shaft 52 and connected by an arm 54, a link 56, a lever 58, and a cam roll (not shown) to a cam 60 mounted on a continuously rotating drive shaft 62 whereupon the gear 50 is oscillated to operate the joggers. Provision is made for adjusting the paths of movement of the joggers thereby to accommodate blanks of different sizes. For a more complete description of the mechanisms thus far described, attention is directed to the parent application.

The machine is provided with four sets of cutters, one set operating at each corner of the blank to form the slots *f* separating the end-wings and the corner-laps and to cut away the corner-laps at *j*. The knives by which the slots and recesses are formed in the upper left-hand corner of the blank shown in Fig. 6 are illustrated in Fig. 4. The recess *j* in the blank is formed by a knife 64 movable downwardly past a cooperating shear block 66 to the position illustrated. A second knife 68 moves downwardly with the knife 64 and cooperates with a shear block 70 to cut the blank along the line *s* (Fig. 7). The portion of the end-wing adjacent to this cut is turned down at *t*

around the edge of a knife 72 by the curved rear portion 74 of the knife 68. The knife 72 is spaced sufficiently from the knife 68 at this time so that there is no cutting action between these knives. After the knife 68 has moved downwardly to the position illustrated, the knife 72 moves in a substantially horizontal plane to trim off the downwardly projecting portion of the blank in the plane of the inner face of the blank, thus giving the appearance shown in Fig. 7. It will be noted that the cover paper *d* provides the end-wing *g* with a finished edge along the slot *f*. Thus, when the box is assembled, this finished edge *t* will appear as indicated in Fig. 8 so that the edge of the layer of shell material is not visible in the completed box.

The mechanisms for operating on the blank at this station are mounted on a pair of carriages 76 (Figs. 1 and 2) mounted on the rails 14 for adjustment lengthwise of the machine. For effecting this adjustment racks 78 are secured to the underside of each carriage near the ends. These racks are engageable with gears 80 mounted on shafts 82 which are supported by bearings 84 secured to the undersides of the rails 14. Each of the shafts 82 has on its outer end a member 86 (Fig. 1) arranged to receive a crank whereby each shaft may be individually rotated to adjust its associated carriage lengthwise of the machine. The carriages are locked in their adjusted positions by gibbs 88 secured to the rails by screws 90.

To each of the carriages is secured a pair of gibbs 92 (Fig. 2) forming between them a slide-way for a pair of slides 94 movable lengthwise of the carriages or transversely of the machine. The slides on each carriage are mounted for similar adjustment toward and away from each other by a screw 96 having right and left hand threaded portions passing through threaded sleeves 98 mounted in blocks 100 (Fig. 2) secured to a side of each slide. These sleeves provide individual adjustment of the slides relatively to each other and are locked in the desired positions of adjustment by set screws 102 engaging grooves in the sleeves. Carried by each of the slides 94 is a bed 104 upon each of which is mounted a pair of shear blocks 66 and 70 (Fig. 2). The inner portion of each bed is secured to its slide by a pair of screws 106 threaded into a rod 108. These rods are journaled in spaced arms projecting from the inner portions of each slide as shown more clearly in Fig. 2. Each pair of screws 106 passes through a bar 110 which engages the upper rearward surface of a bed 104. The screws 106 pass through recesses in the end of the bed as shown in Fig. 2 so that, upon loosening the screws slightly, the bar 110 and the rod 108 may be swung as a unit to free the rearward portion of the bed. Tongue and groove portions 112 between the slide and bed facilitate the proper positioning of the bed on its slide. Other securing means (not shown) may be provided between the outer portions of the slides and beds more firmly to secure them together.

Secured to the outer portions of the beds 104 and extending upwardly therefrom are supporting frames 114 having overhanging arm portions 116 (Fig. 1) for supporting the knives 64 and 68. The lower portions of the supporting frames 114 have dovetail grooves 118 with which cooperate the wedge heads 120 of bolts 122 (Fig. 3) which pass through blocks 124 and receive nuts 126 for rigidly securing the blocks to the frames 114 and the shear blocks 66 to the blocks 124. The blocks 124 may be adjusted along the beds by reason

of the dovetail connection provided by the grooves 118 and the heads 120 of the bolts and by reason also of the fact that the other ends of the blocks 124 are slidably secured to the bed by bolts 128 passing through the blocks 124 and nuts 130 received by a T-slot in the bed (Fig. 1). Heads 134 of the bolts 128 (Fig. 3) hold each shear block 66 against the upper surface of its supporting block 124. The supporting block has a sloping surface 136 for directing the scrap from the blocks. A conveyer belt (not shown) may be provided at the bottom of the machine for carrying material trimmed from the blocks away from the machine. On the front of the supporting blocks 124 toward the entrance end of the machine are adjustably secured guide plates 138 arranged for engagement by the forward edges of the blanks to insure that the blanks will ride smoothly over the blocks.

The shear blocks 70 are carried by supporting frames 140 which are mounted on the beds 104 for adjustment relatively to the shear blocks 66 to vary the distance between the slots *f* and the cutaway portions *j* of the blank. The frames 140 are adjustably secured to the beds 104 by bolts 135 and 137 similar to the bolts 122 and 128. The knives 72 are supported in the frame 140 by rockable members 142 having stud shafts 144 journaled in bearings 146 mounted in arms 148 of the supporting frame 140. The knives 72 are normally maintained in their retracted positions, shown in Fig. 4, by springs 150 acting between arms 152 on the rockable members 142 and recesses 154 in the frames 140. The positions to which the members 142 are moved by the springs are limited by set screws 156 acting against stops 158 secured to the under sides of one of the arms 148 of the frames 140. Rolls 160 are journaled on pins 162 in the arms 148 and are engaged by the back sides of wedges 164 as these move downwardly and support the wedges against lateral thrust. These wedges act on rolls 166 carried by the arms 152 to oscillate the members 142 carrying the knives 72 to trim the downwardly extending portions *t* of the blank (Fig. 4) after the operation of the knives 64 and 68.

The knives 64 and 68 are carried by vertically movable slides 168 (Figs. 1 and 2). The knives are mounted for adjustment relatively to each other upon supporting plates 170 carried by the lower ends of the slides. The opposite sides of the supporting plates are dovetailed as shown in Fig. 1. Each of the knives, as shown in Fig. 3, is provided with ears extending from each end thereof between which pass bolts 172, the heads of which are elongated to underlie the projecting ears on the knives. Each of the bolts extends upwardly through a clamping member 174 having an inclined surface arranged to engage the dovetailed portion of the plate 170, whereby the opposite ends of the knives may be clamped in the desired positions on the plates. Similarly supported by the plates 170 are strippers 176, the work engaging portions of which may be formed of sponge rubber arranged to clamp the blank on the top surfaces of the shear blocks 70 upon downward movement of the knives. The strippers normally extend downwardly below the knives and hold the blanks in position during the return upward movement of the knives until they have cleared the blanks.

The slides 168 are mounted for vertical movement between gibs 178 secured to the overhanging arms 116 of the supporting frames 114. One 75

of the gibs (Fig. 2) is backed up by screws 175 which permits adjustment of the gib toward the other gib to take up for wear. The slides are connected to vertically movable cross-girts 180 which are connected at their opposite ends to cross-heads 182 (Fig. 1) which are in turn secured to the upper ends of vertically movable rods 184. These rods pass through bearings 186 secured to the side rails 14 and through bearings 188 secured to the supporting bars 10. The rods are reciprocated by the shafts 62 which carry eccentrics 190 connected by straps 192 and pivot pins 194 to clamps 196 secured to the rods. The knife-supporting slides are connected to the cross-girts as follows. Threaded through the upper portions of the slides are sleeves 198 providing in their lower ends abutments for springs 200. These springs act against flanges 202 near the upper ends of rods 204, to the bottoms of which are threaded nuts acting on the bottoms of the bushings to prevent downward movement of the bushings on the rods. The upper ends of the rods are provided with heads 207 clamped between bars 206 secured to the under sides of the cross-girts and extending therebetween and gibs 208 secured to the bars. The bars 206 are secured to the cross/girts for adjustment by clamping screws 210 passing through bars 212 resting on the upper surfaces of the cross-girts. These clamping screws are loosened to permit the slides 208 supporting the mechanisms for operating on the blanks to be adjusted transversely of the machine. To permit the lengthwise adjustment of the parts with the carriages 76, the gibs 208 may be loosened so that the upper ends of the rods 204 may slide relatively to the cross bars 206. Auxiliary clamping screws 209 (Fig. 2) threaded through the arms 116 are provided for clamping the slides 168 against downward movement in the frames 114 whenever desired. This may be done whenever the gibs 208 are loosened to permit this lengthwise adjustment of the parts, thus relieving the gibs of the weight of the slides. Springs 211 (Fig. 2) act on the heads of the screws to prevent their accidental turning. When the cross-girts are moved downwardly during the operation of the machine, they act through the springs 209 to move the knives and strippers downwardly to a position limited by the engagement of the lower ends of stop screws 214 with stops 216 in the upper surfaces of the supporting frames 114. Upon further downward movement of the cross-girts the springs 209 will compress, thus permitting the wedges 164 to move further downwardly, as will be described, to actuate the knives 150, thus completing the slotting operation.

The wedges 164 are adjustably clamped to the lower ends of slides 218, which are in turn secured for vertical adjustments by bolt-and-slot connections 220 (Fig. 2) to arms 222 depending from brackets 224. These brackets are connected to the cross-girts 180 between bars 226 and gibs 228. Clamping screws 230 (Fig. 1) passing through bars 223 on the upper surfaces of the cross-girts adjustably secure the bars 226 to the under sides of the cross-girts. Accurate adjustment of the vertical positions of the wedge carrying slides may be effected by screws 232 threaded into the brackets 224 and engaging the tops of the slides 218. Springs 234 act between the slides and pins projecting from the arms 222 to maintain contact of the slides with the heads of the adjusting screws when the slides are adjusted.

From the above it will be seen that the knives are arranged in four sets, one for operating upon each corner of the blank, the sets of knives being in turn arranged in pairs, one pair operating on the leading portion of the blank and the other pair operating on the trailing portion. The pairs of sets are adjusted toward and away from each other by rotation of the shafts 82 which act through the pinions 80 and the racks 78 to move the carriages 76 along the supporting rails 14. In order to permit this adjustment the gibs 88, by which the carriages are locked to the rails, are first loosened and the gibs 208 and 228 associated with the supporting bars 206 and 226, respectively, are also loosened. By means of this adjustment blanks for forming boxes of different widths may be operated upon by the machine. The sets of knives of each pair are also adjustable toward and away from each other to accommodate blanks of different lengths by loosening the screws 210 and 230 and rotating the adjusting screws 96. This moves the slides 94 lengthwise of the carriages 92, these slides supporting the beds 104 and the upwardly extending knife supporting arms 114. After the proper adjustment has been effected, the screws 210 and 230 are tightened to lock the sets of knives in their adjusted positions. For adjusting the knives of each set relatively to each other the bolts 172 by which the knives are clamped to the supporting plates 170 are loosened, thus permitting the knives to be moved along the plate into the desired positions of adjustment.

In the operation of the machine, the blanks are fed by the belts 18 into engagement with the stops 26 into position to be operated upon simultaneously by the four sets of knives. After the blank comes to rest against the stops, the vertical rods 184 are moved downwardly, whereupon the cross-girts 180 carried thereby move the slides 168 and 213 carrying the knives and the wedges, respectively, downwardly toward the blank. The knives 68 and 14 move into the positions shown in Fig. 4, the knives 64 forming the cutaway portions *j* in the outer edges of the corner-laps and the knives 68 forming the slits *s* as illustrated in Fig. 7. At the same time, the surfaces 74 of the knives 68 turn the margins *t* of the end-wings *g* downwardly around the edges of the knives 12. This action of the knives on the blank occurs before the cross-girts 180 have completed their downward movement but further movement of the knives is prevented by engagement of the stop screws 214 with the stops 216. Further downward movement of the cross-girts is permitted by compression of the springs 200 associated with the knife slides and the wedges 164 continue their downward movement acting through the rolls 166 to operate the knives 12. These knives cooperate with the surfaces 74 of the knives 68 to trim the downwardly projecting portions *t* of the blank in the plane of its lower surface, thereby to form the edges of the end-wings as shown in Fig. 7.

Having thus described our invention, what we claim as new and desire to secure by Letters Patent of the United States is:

1. In a machine for making a box blank having end-wings, side-wings and corner-laps, oppositely disposed sets of knives for operating on opposite sides of the blank, each set comprising a knife for trimming the outer edge of a corner-lap and a knife for forming a slot between the corner-lap and the adjacent end-wing, a single adjusting means for moving said sets of knives simultaneously toward and away from each other,

a single adjusting means for moving said sets of knives as a unit in a direction normal to said first direction of movement, and means mounting the knives of each set for adjustment relatively to each other.

2. In a machine for making a box blank having end-wings, side-wings and corner-laps, means for operating on each corner of the blank, said operating means being arranged in pairs, each of said operating means including means for trimming the outer edge of a corner-lap and means for forming a slot between the corner-lap and the adjacent end-wing, single adjusting means for each pair of operating means for moving them simultaneously toward or away from each other, single adjusting means for each pair of operating means for moving the pair as a unit toward or away from the other pair of operating means, and means mounting the trimming means of each of the operating means for adjustment relatively to each other.

3. In a machine for operating upon a box blank, means for forming a slot in the blank comprising means for severing the blank along a line and bending an edge of the severed portion inwardly, and means engageable with opposite sides of the inwardly projecting portion of the blank for severing said portion in substantially the plane of the inner face of the blank.

4. In a machine for operating upon a box blank, means for forming a slot in the blank comprising means for severing the blank upon a line and bending an edge of the severed portion inwardly, and means including said first-named means for severing the inwardly projecting portion of the blank in substantially the plane of the inner face of the blank.

5. In a machine for operating upon a box blank, a shearing member for forming a cut in the blank, said member having a work-engaging face arranged to bend the blank inwardly along the line of cut, and means cooperating with a side of said shearing member for severing the inwardly projecting portion of the blank in substantially the plane of the inner face of the blank.

6. In a machine for operating upon a box blank, a shearing member for forming a cut in the blank, said member having a work-engaging face arranged to bend the blank inwardly along the line of cut, and means operated in response to movement of said shearing member for severing the inwardly projecting portion of the blank against the adjacent side of said shearing member.

7. In a machine for making a blank having end-wings, side-wings and corner-laps projecting from the side-wings, said blank including a sheet of shell material to the outer face of which has been applied a sheet of cover material, a vertically movable member for severing the inner edge of the corner-lap and bending the adjacent edge of the end-wing inwardly, a member movable in a substantially horizontal plane for severing the inwardly projecting portion of the end-wing, and means for sequentially operating said members.

8. In a machine for making a blank having end-wings, side-wings and corner-laps projecting from the side-wings, said blank including a sheet of shell material to the outer face of which has been applied a sheet of cover material, a vertically movable member for severing the inner edge of the corner-lap and bending the adjacent edge of the end-wing inwardly, another member movable in a substantially horizontal plane for severing the inwardly projecting portion of the end-

wing, and means movable with said vertically movable member for operating said other member after the edge of the end-wing has been bent inwardly.

9. In a machine for making a blank having end-wings, side-wings and corner-laps projecting from the side-wings, said blank including a sheet of shell material to the outer face of which has been applied a sheet of cover material, a vertically movable member for severing the inner edge of the corner-lap and bending the adjacent edge of the end-wing inwardly, a member movable in a substantially horizontal plane for severing the inwardly projecting portion of the end-wing, means normally holding said last-named member away from the path of movement of said vertically movable member, a cam roll associated with said horizontally movable member, and a cam movable with said vertically movable member and cooperating with said cam roll for operating said horizontally movable member after the edge of the end-wing has been bent inwardly.

10. In a machine for making a blank having end-wings, side-wings and corner-laps projecting from the side-wings, said blank including a sheet of shell material to the outer face of which has been applied a sheet of cover material, a pair of shearing members movable in a direction at right angles to each other, means for moving one shearing member to sever the inner edge of the corner-lap and to bend the associated edge of the end-wing inwardly, and means for moving the other shearing member to trim the projecting portion of the end-wing against the adjacent side of the shearing member first moved.

11. Those steps in the method of making a blank having end-wings, side-wings and corner-laps projecting from the side-wings, said blank including a sheet of shell material to the outer face of which has been applied a sheet of cover material, which comprises severing the inner edge of the corner-lap and bending the adjacent edge of the end-wing inwardly, and then severing the inwardly projecting portion of the end-wing from one side in substantially the plane of the inner face of the blank while the other side of said portion is supported against lateral movement.

12. In a machine for operating on a box blank, mechanism for forming a slot bounded along one side by a rounded edge comprising means for severing the blank along a line to form the opposite edge of the slot and for bending the severed portion inwardly, and means for severing the inwardly bent portion along a straight line in the plane of the inner face of the blank.

13. Those steps in the method of forming box blanks from a sheet of laminated material composed of a sheet of shell material to the outer face of which has been applied a sheet of cover material which comprises forming a cut in the blank along a line to form one edge of a slot between an end-wing and a corner-lap, bending the material inwardly of the blank to form a rounded edge along the opposite side of the slot and severing the inwardly projecting portion in the plane of the inner face of the blank whereby the cover paper extends over the rounded edge along the opposite side of the slot.

CUTLER D. KNOWLTON.

Certificate of Correction

Patent No. 2,414,109.

January 14, 1947.

CUTLER D. KNOWLTON ET AL.

It is hereby certified that errors appear in the printed specification of the above numbered patent requiring correction as follows: Column 3, line 25, for "dierent" read *different*; column 4, line 70, for "occoperate" read *cooperate*; column 5, line 19, for "blacks" read *blocks*; column 9, line 28, claim 10, for "a direction" read *directions*; column 10, line 6, claim 11, for "comprises" read *comprise*; and that the said Letters Patent should be read with these corrections therein that the same may conform to the record of the case in the Patent Office.

Signed and sealed this 7th day of October, A. D. 1947.
